His Attorney.

UNITED STATES PATENT OFFICE.

ALVIN D. KEENE, OF SCHENECTADY, NEW YORK, ASSIGNOR TO GENERAL ELECTRIC COMPANY, A CORPORATION OF NEW YORK.

ELECTRIC FURNACE-CONTROL APPARATUS.

1,255,613.

Specification of Letters Patent.

Patented Feb. 5, 1918.

Application filed September 5, 1917. Serial No. 189,870.

To all whom it may concern:

Be it known that I, ALVIN D. KEENE, a citizen of the United States, residing at Schenectady, in the county of Schenectady, 5 State of New York, have invented certain new and useful Improvements in Electric Furnace-Control Apparatus, of which the following is a specification.

The present invention relates to electric 10 control apparatus for electric furnaces, particularly for arc furnaces. The object of my invention is to provide means whereby the electrodes may be automatically moved into contact with a stationary conductor at 15 the beginning of the furnace operation to strike the arcs, and to enable the setting of the control apparatus to be changed coincidentally with a change in connections of the energy supply circuit.

20 The novel features of my invention will be pointed out with greater particularity in the appended claims and described in detail in the following description taken in connection with the accompanying drawing 25 which is a diagram illustrating my invention.

Referring to the drawing, the furnace is diagrammatically indicated by a rectangle 1 shown in dotted outline, and comprises a 30 stationary conductor or electrode 2 located at the base of the furnace, and movable electrodes 3, 3' adapted to support arcs in series in conjunction with the stationary electrode 2. These electrodes may either all 35 consist of carbon or graphite, or in some cases, the conductor 2 may be a charge of metal or other conductive material in the furnace. A motor 4 is mechanically connected to the electrode 3 by any form of suitable 40 gearing, the drawing showing a speed reducing gear 5 driven by the motor acting on a nut 6 on the screw threaded rod 7 to raise and lower the electrode. The motor connected to the electrode 3' has not been 45 shown. The electrode is shown as connected to a gearing 8 and it is to be understood that this gearing is connected to a motor and its control apparatus similarly to the motor and control apparatus shown in connection 50 with electrode 3.

The electrodes 3 and 3' are connected respectively to electric mains 9 and 10 receiving electric energy from the secondary of a transformer 11. The contactor magnet 12 55 is connected to the secondary of a current

transformer 13, the primary of which is constituted by a portion of the conductor 9. The armature 14 of the contactor 12 is connected to a lever 15 operating to make contact with either conductors 16 and 17 to 60 complete a separate circuit and thereby to energize either of relay magnets 18 and 19, as will be hereinafter described in greater detail. These magnets in turn control the armature circuit of the motor 4 to raise or 65 lower the electrodes in order to maintain the current in an arc between the electrodes 3 and 2 substantially constant. The winding of a second contactor 20 is connected respectively to the conductor 10, which supplies 70 the electrode 3' and to a conductor 21 which is connected to the electrode 2, thus being responsive to voltage variations of an arc operating between the electrodes 2 and 3'.

The armature 22 of the contactor 20 is 75 connected to a switch lever 23, adapted to contact with either of the conductors 24 or 25 connected to a set of relays and contactors controlling the motor (not shown) for moving the electrode 3'.

By this system of control one series arc 80 being controlled by current variations and a second series arc by voltage variations, uniformity and regularity of arc length and heat intensity is insured.

Examining now the system in greater detail it will be noted that the primary winding of the transformer 11 is divided into two sections 26 and 27. By moving the switch 28 to either include or exclude the section 90 27 in the primary of the transformer, the voltage of the energy supply may be changed. In circuit with the conductor 21 is a fixed resistance 29 and a variable resistance 30. When the switch 28 is moved 95 to make contact with the conductor 31, thus completing the circuit of the supply conductors 32, then the switch 33, mechanically linked to the switch 28, completes a shunt circuit 34 about the resistance 29 and 100 thus automatically "sets" the voltage contactor 20 to operate at a lower range of voltage than is the case when the switch is moved to contact with the tap 35, thereby cutting out the section 27 of the primary 105 winding.

When the furnace is energized the contactor 36 pulls up its armature and causes the switch lever 36^a to complete a circuit between the conductors 37 and 38. In case the 110

energy supply is interrupted the contactor 26 releases and opens the circuit to safeguard the apparatus against injury.

The armature of the current-responsive magnet 12 is in position to complete a circuit from the conductors 39, which are preferably supplied with direct current. To energize the relay magnet 19, the circuit being through the conductors 37, 38, switch 10 lever 15, conductors 16 and 41. The magnet 19 pulls up its armature 42, closes contacts 43 and 44, and energizes the motor 4, the circuit being through the conductors 45, resistance 46, contact 43, conductor 47, the 15 armature of the motor, conductor 48, contact 44, and the conductor 41. The motor is connected to thereupon lower the electrode 3 into contact with the conductor 2. A suitable circuit, for example, a resistance 40, connected across the gap between the electrodes 2 and 3, permits the voltage-responsive contactor 20 to be energized and sets into operation a motor to lower the electrode 3', the control apparatus being like the apparatus energized by the current-responsive contactor 12.

When contact of both electrodes 3 and 3' is established, the electrodes are immediately raised again to strike the arcs. In case of 30 the current-responsive contactor 12, the lever 15 leaves the conductor 16, deenergizing the magnet 19 and opening the contacts 43 and 44. The counter-electromotive force of the motor 4 energizes a contactor magnet 49 connected across the conductors 47, 48, and by the closure of the contact 50, assisted by the spring 51, inserts a resistance 52 in the armature circuit to quickly bring the motor to rest by dynamic braking. While the motor circuit is closed through the resistance 52, a mechanical interlock 54 prevents the closure of the relay magnets 18 and 19, which are attached respectively to interlocks 55 and 56. Upon a flow of current, the 45 contactor lever 15 completes a circuit through the magnet 18, through the conductors 37, 38, 17, 53 and 41. Before the magnet 18 may pull up its armature, the motor must come to a stop and release the mechanical interlocks 54, 55. The same is true upon 50 the reverse operation, the interlock 56 preventing closure of the contacts of the magnet 19 until the motor comes to a stop. When the motor is brought to rest, the relay magnet 18 closes the contacts 57, 58, and energizes the motor to raise the electrode 3, the circuit being completed through the conductors 41, 53, contact 57, conductors 59, 47, the motor armature, conductor 48, contact 58, 55 conductor 60, resistances 61 and 46, and the conductor 45.

Having described the operation of the relay mechanism for the current contactor 12, it will be understood without further detailed explanation how the voltage contactor

operates to lower and raise the electrode 3' so as to maintain an arc of predetermined length. The current of this second arc must necessarily be the same as the current of the arc between the electrodes 3 and 2 as the two arcs are electrically in series.

What I claim as new and desire to secure by Letters Patent of the United States, is:—

1. An electric furnace control apparatus comprising a plurality of electrodes, an electrical circuit connecting said electrodes to operate a plurality of arcs in series, means for controlling one of said arcs in response to variations of the current in said circuit, an electrical connection in shunt to said current-controlled arc and means for controlling another arc in response to voltage variations thereof.

2. An electric furnace equipment comprising arc-supporting electrodes, motors operatively connected thereto, a source of electric energy, supply conductors connecting said source and said electrodes, means for controlling said motors in response to electrical variations in said electrode circuits, means for changing the voltage of the energy supply, and means for automatically changing coincident therewith the setting of said motor control means.

3. The combination of an electric furnace 95 having a stationary electrode, a plurality of movable electrodes adapted to be maintained in arcing relation to said stationary electrode, series supply circuit connections to said movable electrodes, motors operatively connected to each of said respective electrodes, a resistance connected across one of said movable electrodes and said stationary electrode, means for controlling the motor connected to said last mentioned movable 105 electrode in response to current variations in the supply circuit of said electrode, and means for controlling another movable electrode in response to voltage variations across said other movable electrode and said stationary electrode.

4. An electric furnace equipment comprising arc-supporting electrodes, electric motors operatively connected thereto, a source of electric energy, supply conductors connecting said source and said electrodes, a contactor connected to control one of said motors in response to the variations of the current in the respective electrode circuit, a second contactor connected to control a second motor in response to variations of potential of an arc supported thereby, means for changing the voltage of said energy supply source, and means for automatically changing the setting of said contactors when the 125 voltage of said supply source is changed.

5. An electric furnace equipment comprising a stationary electrode, two movable electrodes co-operating therewith to operate two arcs electrically in series, a transformer for 130

supplying electric energy to said electrodes to maintain said arcs, connections for changing the ratio of transformation in said transformer to change the secondary voltage 5 thereof, means for adjusting said movable electrodes with respect to said stationary electrode to maintain said arcs of uniform length, and means for automatically changing the setting of said adjusting means when 10 changing the connections of said supply transformer.

6. An electric furnace apparatus comprising two movable electrodes, a stationary furnace conductor, an electrical circuit for said

electrodes for operating a plurality of arcs 15 in series between said movable electrodes and said stationary conductor, motor-operated means for adjusting one of said movable electrodes in response to variations of the current in said circuit, a resistance in 20 shunt to the arc from said current-controlled electrode, and motor-operated means for adjusting the second electrode in response to voltage variations in said circuit.

In witness whereof, I have hereunto set 25 my hand this 4th day of September 1917.

ALVIN D. KEENE.
